CLAIM

The ornamental design for a windshield stand, as shown and described.

DESCRIPTION

FIG. 1 is a perspective view of the windshield stand.

FIG. 2 is a perspective view of the windshield stand shown in a position of use, with an unclaimed windshield shown in broken lines and forming no part of the claimed design.

FIG. 3 is a front view of the windshield stand.

FIG. 4 is a right side view of the windshield stand.

FIG. 5 is a bottom view of the windshield stand.

FIG. 6 is a left side view of the windshield stand.

FIG. 7 is a back view of the windshield stand; and,

FIG. 8 is a top view of the windshield stand.
